UNITED STATES PATENT OFFICE

EUGENE L. BAKER, OF TAUNTON, MASSACHUSETTS

ELEVATOR

Application filed February 17, 1930. Serial No. 429,148.

Sometimes a person on an elevator will permit his foot to protrude enough to be caught under a fixed portion of the floor of a building, when the elevator moves up; or a person standing on the floor of a building may permit his foot to protrude enough to be caught under an elevator going down; and this invention aims to provide a means whereby carelessness of the sort alluded to will not be attended by serious consequences.

Figure 1 of the drawings is a section showing one of the floor pieces in their normal state; Figure 2 is a vertical section showing one floor piece raised; Figure 3 is a top plan; Figure 4 is a bottom plan; and Figure 5 is a vertical section showing a modification.

The numeral 4 marks an elevator raised and lowered by any suitable means 5 on guides 20 in a shaft 3 in a building 1, the numeral 2 marking one of the many landing floors that the elevator may pass.

The elevator 4 has an upwardly movable floor section 6 connected by hinges 7 with the floor of the elevator, and the floor 2 has an upwardly movable section 8 connected to the floor by hinges 9. The floor sections 6 and 8 may be angle members having depending flanges that bear, respectively, against the edge of the floor of the elevator 4 and against the edge of the floor 2 in the building 1, to take some of the strain off the hinges 9 and 7. Under the floor section 6 is located a guard or signal strip 10 that is hinged at 11 to the floor of the elevator for upward swinging movement. Flexible elements 12, connected to the ends of the guard 10 and to the floor of the elevator 4, hold the guard 10 in a horizontal position, against downward swinging movement. The guard 10 is made out of light material, such as wire netting. A like guard or signal strip 14 is hinged at 15 to the floor 2 of the building 1, under the floor section 8, and is sustained from the floor 2 by flexible elements 16 connected to the guard and to the floor.

If a person stands in the elevator 4 with his foot 19 in protruding position, the guard 14 and the floor section 8 will swing upwardly without injury to the foot, when the elevator 4 moves up past the floor 2. If a

person is standing on the floor section 8 with his foot protruding into the shaft 3, the guard 10 and the floor section 6 will swing up, as the elevator moves down, and the person's foot will not be injured. The light strips 10 and 14 often give a person a warning signal in time so that he can jerk back his foot without having to raise the floor section 6, or the floor section 8. This is a particularly good feature if, when the foot 19 sticks out, as in Figure 2, there happens to be a weight of some kind on the movable section 8. The same argument holds if the foot protrudes beyond the section 8, there being a weight of any sort in the elevator 4, on the movable section 6.

In heavy constructions, it may be undesirable to have the foot carry all the weight due to lifting the movable floor sections. Then recourse is had to the structure of Figure 5, wherein compressed springs 17 are located in tubular receptacles 18 under the hinges 7a and 9a. Other springs may be used, if desired, to reduce the weight that the protruding foot has to raise. In Figure 5, parts hereinbefore described have been designated by numerals previously used, with the suffix "a".

I claim:

1. In improvements in elevator construction, a landing and an elevator movable vertically with respect to the landing, each including a fixed floor section, a movable floor section hinged to one of the fixed floor sections for upward swinging movement, and a signal strip located below the movable floor section and hinged to the said fixed floor section for upward swinging movement, the signal strip being lighter than the movable floor section, whereby the said strip will strike a protruding foot and afford a warning signal before the foot comes into contact with the movable floor section, the movable floor section lying above the signal strip to protect the signal strip against injury during the movement of passengers and goods to and from the elevator.

2. In improvements in elevator construction, a landing and an elevator movable vertically with respect to the landing, each including a fixed floor section, an upwardly foldable hinge mounted on the upper surface

of one of the fixed floor sections, and a movable floor section made up of an angle member comprising a substantially horizontal flange attached to the hinge, and a substantially vertical flange extending downwardly along the edge of the said fixed floor section, to serve as a reenforcement for the hinge.

3. In improvements in elevator construction, a landing and an elevator movable vertically with respect to the landing, each including a fixed floor section, an upwardly foldable hinge mounted on the upper surface of one of the fixed floor sections, a movable floor section made up of an angle member comprising a substantially horizontal flange attached to the hinge, and a substantially vertical flange extended downwardly along the edge of the said fixed floor section to serve as a reenforcement for the hinge, and a compression spring housed in the said fixed floor section and located underneath the hinge, the spring cooperating with the hinge to aid in raising the movable floor section when an object is engaged therebeneath, as the elevator moves vertically with respect to the landing.

4. In improvements in elevator construction, a landing and an elevator movable vertically with respect to the landing, each including a fixed floor section, an upwardly foldable hinge mounted on the upper surface of one of the fixed floor sections, a movable floor section made up of an angle member comprising a substantially horizontal flange attached to the hinge, and a substantially vertical flange extended downwardly along the edge of the said fixed floor section to serve as a reenforcement for the hinge, a compression spring housed in the said fixed floor section and located underneath the hinge, the spring cooperating with the hinge to aid in raising the movable floor section when a protruding foot is engaged therebeneath, as the elevator moves vertically with respect to the landing, and a signal strip located below the movable floor section and hinged to the said fixed floor section for upward swinging movement, the signal strip being lighter than the movable floor section, whereby the said strip will strike a protruding foot and afford a warning signal before the foot comes into contact with the movable floor section.

In testimony that I claim the foregoing as my own, I have hereto affixed my signature.

EUGENE L. BAKER.
